UNITED STATES PATENT OFFICE.

CHARLES H. W. RELYEAE, OF NORTH ADAMS, MICHIGAN.

CAR-COUPING.

SPECIFICATION forming part of Letters Patent No. 518,745, dated April 24, 1894.

Application filed January 17, 1894. Serial No. 497,122. (No model.)

To all whom it may concern:

Be it known that I, CHARLES H. W. RELYEAE, a citizen of the United States, residing at North Adams, in the county of Hillsdale and 5 State of Michigan, have invented certain new and useful Improvements in Car-Couplers; and I do hereby declare the following to be a full, clear, and exact description of the invention, such as will enable others skilled in the 10 art to which it appertains to make and use the same.

My invention relates to an improvement in car couplers.

The invention will first be described in connection with the accompanying drawings, and then particularly pointed out in the claim.

In the drawings—Figure 1 is a plan view of two couplers in their locked or coupled position. Fig. 2 is a side view of one of the couplers. Fig. 3 is a front view of the same. Fig. 4 is a longitudinal sectional view of the same. Fig. 5 is a horizontal sectional view of the same.

Referring to the drawings, A is a draw head 25 having a forked or bifurcated front consisting of an upper or top plate, a, and a lower plate a', these plates preferably being cast integral with the draw head. In the inner face of each plate is formed a recess a² for a purpose 30 pose hereinafter described, a pin hole a³ being formed in each plate near the end of each recess, the pin holes being in register with each other. The upper plate is provided, near the end of the draw head, with a longitudinal slot 35 a⁴ and in the lower plate immediately below this slot is formed a recess a⁵, sloping at its bottom, being deepest near its front end and inclining upward toward the rear. To the top of the top plate is attached a pair of ears a⁶, 40 one on each side of the slot, a⁴, each ear having a bolt hole, a⁷, for a purpose hereinafter referred to. The front end of each plate is rounded off, as at, a⁸.

Between the upper and lower plates is provided a movable jaw, B, which has an enlarged head, b, projecting beyond the plates, being concaved as at, b', these concavities fitting against the rounded portions, a⁸, of the plates. The jaw, B, has a pair of lugs b³ which fit in 50 the recesses a² in the plates, being smaller than said recesses, and thereby permitting a

limited amount of angular motion of the jaw. A pin hole passes through the jaw near the ends of the lugs, as at b⁴, this pin-hole registering with the pin-holes a³ in the plates; a 55 heavy pin or bolt C passing through the holes in the plates and in the jaw and serving to pivotally hold the jaw. This pin is arranged to be in the longitudinal central vertical plane of the draw head, in order that all lateral 60 strains may be avoided. The jaw is provided with a transverse arm b⁵ which is engaged by the jaw of the opposite coupler, in coupling two cars, and is forced backward, thereby swinging its own jaw into engagement with 65 the jaw of the opposite coupler. The said transverse arm normally rests against a projecting shoulder a⁹ which is cast integral with the upper and lower plates, this shoulder receiving the impact of the opposite coupler. 70 The front end of the jaw has a pair of laterally extending lugs b⁶ which have link-pin holes b⁷ to receive the ordinary link-pin when necessary to couple a car provided with my improved coupler to an ordinary link-pin 75 coupler. The rear end of the jaw is provided with a rearward and laterally extending spur b⁸ having a diagonal slot b⁹.

In the ears a⁶ is pivoted a coupling dog or pin D, having two arms at an obtuse angle 80 with each other, as shown, a bolt E, passing through the holes a⁷ and through a bolt hole d in the dog D and serving as a fulcrum. The short arm d' of the dog normally rests on the upper surface of the top plate and is weighted 85 at its forward end, as shown at d², being also provided with a lug d³ having a hole d⁴, as shown. The long arm d⁵ of the dog extends downward and backward, passing through the slot a⁴ and normally resting with its lower 90 end in the shallowest part of the recess, a⁵, the said long arm being adapted to swing forward when the weighted end of the short arm is raised, and when thus swinging forward to engage the diagonal slot b⁹ in the jaw B, and 95 thus to crowd the inner end of the jaw to one side, thereby swinging the front end of the jaw in the opposite direction and serving to move the jaw into its uncoupled position. In order that the long arm of the dog may move 100 with less friction in the diagonal slot it has its corners beveled as at d⁶, d⁷, and d⁸.

In order to raise the front end of the short arm of the dog D and thereby uncouple the jaw from any opposite one with which it may be engaged, an operating shaft F is provided being mounted in bearings f, fixed on the car and having a cranked outer end f' and an inner end f² cranked at right angles to the outer end, the latter cranked end being attached by a link G to the lug d³ of the dog D in any suitable manner.

The operation of my improved coupler is obvious from the description above given.

Having thus fully described my invention, what I claim as new, and desire to secure by Letters Patent, is—

In a car coupler, the combination of a draw head having its extremity bifurcated whereby a top plate and a bottom plate are formed, the said top plate and bottom plate provided with registering pin holes extending through them and having on their adjacent faces recesses a², extending radially from said pin holes, the

jaw B, pivoted at the pin holes in said top and bottom plates and provided on opposite sides with projections or lugs of less width than and arranged in the recesses in the adjacent faces of said plates, said jaw having a lateral lug at its forward end and a transverse arm between said shoulder and the pivot point, said arm engaging when in its locked position some fixed portion of the draw head, the rear end of the jaw being provided with an inclined slot, and an uncoupling lever D, pivoted in the draw head behind the rear end of the jaw and in position to engage the inclined slot therein, said lever having its upper end weighted and bent forward, substantially as set forth.

In testimony whereof I affix my signature in presence of two witnesses.

CHARLES H. W. RELYE A.
